CHILD'S COMBINED DESK AND TOY CHEST
OR THE LIKE

Paul Metro, Brookfield, Ohio

Application March 16, 1948, Serial No. 145,117

Term of patent 14 years

(Cl. D33--11)

To all whom it may concern:

Be it known that I, Paul Metro, a citizen of the United States, residing at Brookfield, in the county of Trumbull and State of Ohio, have invented a new, original, and ornamental Design for a Child's Combined Desk and Toy Chest or the like, of which the following is a specification, reference being had to the accompanying drawing, forming a part thereof.

In the drawing:

Figure 1 is a perspective view of the combined desk and toy chest, showing my new design, and

Figure 2 is a view similar to Figure 1, with the top of the desk in raised position and part of the support broken for purposes of illustration.

The characteristic features of my design reside in those portions shown in full lines in the drawing.

I claim:

The ornamental design for a child's combined desk and toy chest or the like, substantially as shown and described.

PAUL METRO.
